OIL BURNER

Filed Aug. 20, 1928

Fig. 1

Fig. 2

Fig. 4

A diagram of a rectangular frame with various numbered components. The frame has a central rectangular area with a horizontal line through it. Numbered callouts point to specific parts: '9' points to the top edge; '12' points to the top center; '8' points to the top right corner; '14' points to the right edge; '33' points to the right center; '3' points to the bottom left corner; '25' points to the bottom center; '22' points to the bottom right corner; '23' points to the bottom right center; '26' points to the bottom right edge; '5' points to the left edge; '24' points to the bottom left center; and '13' points to the bottom left edge. There are also dashed lines indicating hidden edges and a small '20' at the bottom right.

A cross-sectional diagram of a cartridge assembly. It features a base plate (36) with a central cavity. A cylindrical component (37) is seated in this cavity. A ribbed cylindrical tube (38) is positioned over the top of component 37. A central tube (39) extends through the center of the assembly. A thin metal strip (40) is attached to the side of the central tube. A small cylindrical component (41) is located at the base of the central tube. A ribbed cylindrical tube (42) is attached to the side of the central tube. A thin metal strip (43) is attached to the side of the ribbed tube 42. A small cylindrical component (44) is attached to the side of the ribbed tube 42. The entire assembly is shown in a perspective view with various components labeled with numbers.

UNITED STATES PATENT OFFICE

GEORGE L. BARNES, OF EVERETT, WASHINGTON

OIL BURNER

Application filed August 20, 1928. Serial No. 300,767.

My invention relates to an oil burner nozzle. More particularly, my invention relates to an oil burner nozzle designed to cause the atomization of crude oil fuel by means of a fluid under pressure such as steam or compressed air as occurs in combustion chambers.

For purposes of clearness and definiteness of description and illustration, I will set forth my invention as applied to the conditions obtaining in the combustion chambers of railway locomotives and steam boats, but it is to be understood that my invention is not to be limited to any such specific application, but extends to all combustion chambers 15 where like conditions and problems obtain.

A primary object of my invention is to provide such an oil burner as will be characterized by its simplicity of construction and economy of manufacture. The importance 20 of simplicity of construction involves not only economy of manufacture but also extends to the facility with which it may be applied and removed whenever trouble develops, even though the device may be at a 25 distance from any machine shop, the ordinary kit of tools on the vehicle being sufficient for any necessary dismounting or reassembling. I purpose providing such a burner that the time involved in any such removal is 30 negligible.

A further primary object of my invention is to provide an oil burner which may be readily adjusted and adapted and installed in any of the standard types of combustion 35 chambers. At the present time there are varying types of fire boxes obtaining in locomotive construction. In some the brick-lined floor of the fire box is horizontally disposed. In others it is positioned at an angle to the 40 horizontal. The pipes serving as conductors for the fuel and the steam are installed to meet the particular type of fire box involved. A primary object of my invention is to provide an oil burner which will be applicable to 45 any of these various types of combustion chambers without any substantial change in the fittings or bending of the pipes and one in which the burner may take the position of the burner for which the particular fire box was 50 originally designed. To this end I purpose

providing a burner nozzle characterized by providing a flame, the direction of which may be adjustable.

Furthermore, a primary purpose of my invention is to provide an oil burner nozzle 55 which will maintain itself relatively clean and free of carbonized fuel products, particularly as respects the outlet ports of the nozzle. At the present time serious objection obtains to burners in that when the burner is 60 shut off liquid fuel tends to remain in the burner or tends to drip back along the nozzle and become hard baked in the nozzle openings due to the heat remaining in the fire box after 65 having been in operation. I purpose providing a burner which avoids this difficulty.

Furthermore, a primary purpose of my invention is to provide an oil burner which saves the fuel, provides a better atomization to the end that less carbonizing occurs so that 70 the linings of the chamber and the flues are both free of soot to any objectionable extent, and finally it is my purpose to provide a burner which gives a much cleaner and whiter flame than has heretofore been provided. 75

The above mentioned general objects of my invention, together with others inherent in the same, are attained by the device illustrated in the following drawings, the same being preferred exemplary forms of embodiment of my invention, throughout which drawings like reference numerals indicate like parts:

Figure 1 is a plan view of a burner embodying my invention;

Fig. 2 is a view in longitudinal central section of Fig. 1;

Fig. 3 is an end view of the same;

Fig. 4 is a plan view of a modified form of burner embodying my invention;

Fig. 5 is a view in longitudinal section on line 5, 5 of Fig. 4;

Fig. 6 is a view in cross section on line 6, 6 of Fig. 4;

Fig. 7 is a fragmentary sectional view of a modification of the form shown in Figs. 1, 2 and 3; and

Fig. 8 is a view of a still further modified form with particular reference to the form shown in Figs. 1, 2 and 3.

The oil burner device embodying my invention is comprised in general of two parts, the outer member or housing 8 and the inner gaseous fuel conductor member 9. The inner member 9 may be provided with a boss 10 into which a nipple 11 may be screwed, thereby holding the inner member as respects the inlet end axially disposed within the housing 8. The inner member as respects its tip is provided with upper and lower converging faces 12 and 13, i. e., with similarly angularly disposed faces. Likewise, said inner member is provided with two similarly laterally disposed faces 14 and 15. These faces in the form shown in Figs. 1, 2 and 3 are straight and parallel each other, i. e., they are similarly angularly disposed. The forward or inner or burner end of the housing member 8 is provided with two converging faces 16 and 17 which substantially parallel faces 12 and 13 of the inner member 9. The housing member 8 also has lateral faces 18 and 19, which substantially parallel faces 14 and 15 of the inner member 9. Set screws 20 and 21 operatively disposed in housing member 8 function as adjusting means whereby the faces 12 and 13 of the inner member 9 may be held in predetermined spaced relation to the faces 16 and 17 of the housing member 8. This provides for directing the sheet of flame at the desired angle to a plane passing through the axis of the device and paralleling the walls 22 and 23, which form the boundary of the outlet port 24 of the inner member 9. The walls 25 and 26 complete the boundary walls of said port 24.

Liquid fuel such as crude oil enters through the nipple 11 and into the conduit 27 and is caused to flow therethrough, either under pressure or by gravity. Through inlet 28 formed in a demountable cap 29 suitably secured to housing member 8 by means of screws 30, fluid under pressure, such as steam or air, enters the conduit 31 formed between the inner member 9 and the outer housing member 8. The steam upon discharging through the constricted opening 32 and through the constricted opening 33 is directed with much force against the oil stream issuing from port 24, breaking the same up into very minute particles and causing complete atomization of the same. It will be noted that port 33 formed on face 19 is preferably only of a width substantially equal to the width of the port 24, thereby leaving portions of the face 19 to function as means to hold the burner end of inner member 9 in position.

In the modified form shown in Fig. 8, the cap 29 is formed integrally with the housing member 8 and the inner member 9 is inserted through the burner end of housing 8. The end portions of housing 8 are demountable in this modified form and are releasably held in this position by means of screws 34 and 35.

The advantage of this form is that the burner is more readily cleaned.

In the modified form shown in Figs. 4, 5 and 6, a burner is shown of a type which provides a fan-shaped flame particularly designed for marine and stationary boiler installations. The outer housing member 36 encloses inner member 37. The faces of this modified form are similar in all respects to the form shown in Figs. 1, 2 and 3 with the exception of the lateral faces 38 and 39 of the inner member which are diverging with respect to each other, i. e., said oppositely disposed faces are similarly angularly disposed. Corresponding with these faces of the inner member 37, the housing member 36 has faces 40 and 41 divergingly, i. e., similarly angularly disposed, paralleling faces 38 and 39. Here likewise faces 40 and 41 are provided with restricted faces 42 and 43, which are of a height substantially equal to the width of the outlet port 44, the remaining portions of the faces 40 and 41 functioning to assist in holding the burner end portion of the inner member 37 in position. Inner member 37 in this modified form may be provided with lugs 45 on the inlet end of the burner which assists in holding the inner end of the inner member in axial position within the housing member 36. A liquid fuel or oil pipe, not shown, which conducts the oil to the inner member and which may be screwed into the inner end portion of the inner member 37, likewise may hold the said end portion in axial position. A coupling on the end of the steam or air pipe, not shown, drawn tight upon the bearing 46, serves to lead the steam to the chamber 47 surrounding the inner member 37. The mode of operation of this modified form is in all respects similar to that shown in Figs. 1, 2 and 3.

In the modified form of inner member shown in Fig. 7, a drip groove 48 is preferably provided so that when the operation of the burner is interrupted, any oil that may tend to flow down the face 13 is stopped and compelled to drip into the combustion chamber which is ordinarily in a very heated condition immediately after cessation of operation of the burner. Obviously, drip groove 48 prevents the fuel from running back to port 32 and becoming carbonized therein, so that the burner automatically maintains itself in a clean condition both as respects the port 32 and conduit 30. This has been found in operation to serve a highly important function in maintaining the said burner in an operatively clean condition. I preferably provide said groove 48 in both faces 12 and 13, so that the burner can be installed in an inverted position if desired.

By providing a burner which has the inner member adjustable and thereby providing for disposing the flame at any desired angle, my burner is adapted to be installed in any

of the standard types of combustion chambers now in use with the minimum of alteration of the mounting means. The burner thus described embodying my invention in any of its forms is characterized by simplicity of construction. Said housing and inner member may be cast and the only machining required is confined to providing the faces on the burner end of the burner and the drip groove 48. In the modified form shown in Figs. 4, 5 and 6, the bearing for the fluid, such as steam or air, under pressure is also machined.

In actual operation on one of the trans-continental railroads it has been found that this burner saves fuel to the extent of ten to twenty-eight percent over the standard type of burner now commonly employed, and the burner embodying my invention is characterized by maintaining the linings and flue free of soot and providing a cleaner and whiter fire than heretofore. Repeated installations indicate that the burner embodying my invention provides a much better atomization of the fluid fuel than has been heretofore obtained.

Obviously, changes may be made in the forms, dimensions and arrangement of the parts of my invention, without departing from the principle thereof, the above setting forth only preferred forms of embodiment.

I claim:

1. An oil burner embodying two independently constructed members, namely, a housing member and an inner fluid fuel conductor member, the burner end portion of which extends beyond the end of said housing member, the burner outlet of said inner member being of rectangular form in cross section, said end portion having its opposite exterior faces angularly disposed, said housing end portion having faces paralleling the adjacent said faces of the inner member; adjusting means operatively disposed in the burner end portion of the housing whereby one pair of the said faces of the inner member may be held in predetermined spaced relation to the adjacent pair of the said faces of the housing member so that the direction of the flame may be controlled in two opposite directions; and means at the end opposite the burner outlet whereby said inner member may be held in spaced relation to the housing member.

2. An oil burner embodying two independently constructed members, namely, a housing member and an inner fluid fuel conductor member, the burner end portion of which extends beyond the end of said housing member, the burner outlet of said inner member being of rectangular form in cross sections, said end portion having its opposite exterior faces angularly disposed, said housing end portion having faces paralleling the adjacent said faces of the inner member, one pair

of oppositely disposed faces of the housing member holding the inner member in position; adjusting means operatively disposed in the burner end portion of the housing whereby one pair of the said faces of the inner member may be held in predetermined spaced relation to the adjacent pair of the said faces of the housing member so that the direction of the flame may be controlled in two opposite directions; and means at the end opposite the burner outlet whereby said inner member may be held in spaced relation to the housing member.

In witness whereof, I hereunto subscribe my name this 9th day of August, 1928.

GEORGE L. BARNES.
